C. F. A. BOLDT,

NEEDLE THREADER.

APPLICATION FILED OCT. 23, 1918, RENEWED JULY 27, 1920.

1,356,336.

Patented Oct. 19, 1920.

UNITED STATES PATENT OFFICE.

CHARLES F. A. BOLDT, OF MCINTOSH, MINNESOTA.

NEEDLE-THREADER.

1,356,336.

Specification of Letters Patent. Patented Oct. 19, 1920.

Application filed October 23, 1918, Serial No. 259,371. Renewed July 27, 1920. Serial No. 399,443.

To all whom it may concern:

Be it known that I, CHARLES F. A. BOLDT, a citizen of the United States, residing at McIntosh, in the county of Polk and State 5 of Minnesota, have invented certain new and useful Improvements in Needle-Threaders, of which the following is a specification.

This invention relates to the class of apparel apparatus, and more particularly to a 10 needle threader.

The primary object of the invention is to provide a needle threader of novel and simple construction, particularly designed for threading darning needles or sacker needles, 15 that is large needles in general and particularly for use by those repairing and fastening sacks of cloth for containing various articles of merchandise.

A further object of the invention is to 20 provide an improved needle threader having means for holding a needle in novel relation to a threading device capable of adjustment to suit needles of various sizes, and to provide in conjunction with a plate forming 25 the body of the device, a cutter for thread, string, cord or twine used.

With the above and other objects in view, as will appear as the description proceeds, the invention comprises the novel features 30 of construction, combinations of elements and arrangement of parts which will be more fully described in the following specification and then finally embodied in the clauses of the claims which are appended 35 hereto and which form an essential part of the same.

Reference is had to the accompanying drawings forming a part of the application, wherein like reference characters will refer 40 to corresponding parts throughout the several views, in which—

Figure 1 is a face view of my improved needle threader,

Fig. 2 is a front elevation thereof,

Fig. 3 is a plan view,

Fig. 4 is an enlarged longitudinal sectional view taken on the line 4—4 of Fig. 1, and

Fig. 5 is a horizontal or longitudinal sec- 50 tional view taken on the line 5—5 of Fig. 1.

Referring to the drawings in detail, my

improved needle threader is shown as comprising a substantially rectangular plate 10 having in the central portion thereof an opening 11 for suspending the same upon a nail or hook or the like. The front and bottom edges 12 and 13 respectively, are made rectilinear, while the top edge is provided with a series of arcuate recesses 14 producing rearwardly extending hooks 15 which are open as shown, while the rear edge is made of fanciful curvature and at its central portion, is provided with a slot 16 communicating with a circular portion 17 into which projects a knife blade 18 riveted or otherwise secured to the plate 10 as shown at 19 and designed to be used for cutting thread, string, cord or twine. Mounted at spaced points longitudinally or horizontally of the plate 10 and upon opposite sides thereof, are opposed spring strips 20 flared outwardly at their ends, and as said strips are secured to the plate upon opposite sides thereof, as by riveting or the like as shown at 21, and near their inner ends, the free 70 extremities projecting beyond the edge 12, extend in opposite directions to guide the needle designated at 22 therebetween, the springs serving as jaws or holders, to retain the needle in position parallel or adjacent to 75 the edge portion 12.

The needle threading device proper is positioned at the upper portion of the plate 10 and for this purpose said plate is provided with spaced vertical slots 23 providing intermediate portions 24 bent in opposite directions to form open loops adapted to receive the shank portion 25 of a hook 26 therethrough. This shank portion is provided upon opposite sides with grooves 27 80 adapted to receive the inwardly projecting portions 28 of opposed slotted clamping jaws 29, the slots of which are designated 30, and which are held in clamping engagement with the shank of the hook to permit adjustment 85 thereof horizontally or longitudinally of the plate 10, through the medium of a binding screw 31, which latter also engages through the slot 30 and a slot 32 in the plate 10 coincident therewith. The hook 26 is in the 90 form of a bladed member having an upturned free end with notches 33 therein,

adapted to catch the thread in the threading operation as will be hereinafter more particularly set forth.

It will thus be seen that the hook 26 through the medium of the shank thereof, can be adjusted horizontally or longitudinally of the plate 10 and disposed above said hook is a spring 34 comprising a section of 5 spring steel wire or the like rebent intermediate its ends and having the extremities thereof extended in opposite directions, as shown at 35 to project through a slot 36 in the plate 10 above the slot 32 and clamping jaws 29, preferably rearwardly thereof. The 10 opposed portions of the spring extend upon opposite sides of the plate, the inwardly projecting extremities 35 being located one ahead of the other and positioned in overlapping relation through the slot 36, as is 15 clearly shown in Fig. 5 of the drawings. The relation of the parts for holding the shank of the hook 26, is clearly shown in Fig. 4 of the drawings and this fastening means is located immediately below the fastening means for the spring 34, the free 20 end or bight portion of which is preferably bent upwardly as more particularly shown in Fig. 1 of the drawings, in a slight arc, over the hook 26 so as to overlie the 25 extremity thereof. In order to hold the spring in position, clamping jaws vertically disposed and indicated at 37 are engaged by the clamping screw 31 outwardly of the jaws 29 and have inwardly projecting portions at 30 their upper ends extending over the shank portions of the spring 34, thereby effectively holding said spring in position upon or straddling the plate, with the free end or bight portion thereof downwardly displaced. 35

In the threading operation, the plate of the device is held in one hand between the thumb and forefinger and the end of the thread between the second and third finger and run through one of the open guide 40 hooks 15 on top of the instrument or plate. The thread is then extended between the hook 36 and spring 34 to engage beneath the overhanging or projecting portion of said spring 34 and thereafter pressed slightly so 45 as to be caused to enter between said spring and the hook 26 until the thread is above the hook and against the needle, which latter is passed between the spring clamp so that the eye will pass over the hook 26, the needle 50 being so mounted prior to running the thread or cord between the hook and the spring as specified. Now with the thread drawn downwardly toward the lower end of the needle, that is the pointed end, and on manipulating the device, the eye of the needle 55 is caused to move over the hook and by reason of the fact that the thread is engaged in one of the notches 33 in said hook, the thread will be held on the hook 26, while 60 the eye moves over the same, thereby effect- 65

tively threading the needle quickly and accurately without the usual annoyance by the customary method of threading. The device is made in various sizes, but one size will accommodate needles as small as a small size 70 darning needle and as large as a medium size sack needle, without interfering with the threading operation. Also, by adjusting the hook and spring, as previously specified, the device may be made to accommodate needles 75 of different sizes and as the inner end of the hook 26, that is the inner end of the shank portion 25 thereof, is received within a slot 38, said hook is effectively held in position.

From the foregoing description taken in 80 connection with the accompanying drawings, it is thought that a clear and comprehensive understanding of the construction, operation and advantages of my invention may be had, and while I have shown and described 85 the device as embodying a specific structure, I desire that it be understood that such changes may be made in said structure as do not depart from the spirit and scope of the invention as claimed. 90

Having thus described my invention, what I claim as new, and desire to secure by Letters Patent, is:

1. A needle threader comprising a substantially rectangular plate, outwardly flaring clamping members secured upon opposite sides of the plate and projecting from one edge thereof to receive a needle therein, said plate having vertical slots providing intermediate portions bent outwardly, a flat 95 hook having a shank portion extending through said offset portions having opposed recesses at its inner end, means for clamping and adjusting said shank longitudinally of the plate, said hook having an upturned 100 portion with notches at its inner edge and a spring comprising a U-shaped member with its bight portion disposed above the hook and extending upon opposite sides of the plate, and clamping means co-operative with 105 the aforesaid clamping means to secure said spring in position.

2. A needle threader comprising a plate-like body, means carried by the body for holding a needle adjacent to one edge thereof, said plate having loop portions near one edge thereof, a hook having a shank adjustable in said loop portions, said hook being flat and projecting from one edge to receive the eye of the needle thereover, said hook 115 having a notched edge portion disposed toward the plate, said plate having a slot therethrough in the direction of the shank of the hook, clamping members disposed upon opposite sides of the plate and having 120 slots therein, said clamping members engaging the shank to permit adjustment of the latter longitudinally, said plate also having a slot therein above said first mentioned slot, a spring including a section of spring metal 125 130

bent intermediate its ends with the bight portion thereof disposed upon opposite sides of the hook and directed upwardly over the same, said spring having inwardly directed 5 extremities engaging said second named slot, clamping members disposed outwardly of said first named clamping members and engaging the opposite sides of the spring, and

a clamping screw engaged through said clamping members and plate, for binding 10 said parts or permitting adjustment or removal thereof as desired.

In testimony whereof I affix my signature hereto.

CHARLES F. A. BOLDT.
